UNITED STATES PATENT OFFICE.

WILLIAM RODIGER, OF CHICAGO, ILLINOIS.

DESIGN FOR AN INKSTAND.

SPECIFICATION forming part of Design No. 22,003, dated November 22, 1892.

Application filed November 17, 1890. Serial No. 371,762. Term of patent 14 years.

To all whom it may concern:

Be it known that I, WILLIAM RODIGER, a citizen of the United States, residing at Chicago, in the county of Cook and State of Illinois, have invented and produced a new and original Design for an Inkstand, of which the following is a specification, reference being had to the accompanying drawings, forming a part thereof.

10 In said drawings, Figure 1 is a perspective view of an inkstand showing my design. Fig. 2 is a top plan view thereof.

15 My design consists in the new shape and configuration of an inkstand, as hereinafter set forth, and shown in the drawings.

20 In said drawings, A indicates the body portion of the inkstand. The exterior configuration of said body portion A approximates that of a parallelopiped, insomuch that if its sides were extended in straight lines the re-

25 sultant body would have the shape of a parallelopiped. The said body portion has the two straight long sides a and the two straight short sides a' , which are arranged substantially at right angles to said long sides a . The said straight sides a and a' are joined by curved portions a^2 a^3 , which are located correspondingly to the vertical corners of a parallelopiped. It will be noted in this con-

30 nection that although it is usual to round off the corners of inkstands, yet the radius of the curve of said curved portions a^2 is greater in proportion than the curve of the ordi-

nary rounded-off corners of glass objects and gives the inkstand a graceful and pleasing 35 appearance.

The top a^3 of the inkstand is substantially flat, and to one side thereof and approximately parallel with the long sides a is located a groove or longitudinal depression a^4 , 40 providing a pen-groove. The mouth a^5 of the inkstand is located to one side of the pen-groove a^4 and substantially at one end of the inkstand. The said mouth a^5 rises from an annular bead a^6 , formed on the top a^3 of the 45 inkstand, which bead is curved the same as the said curved portions a^2 , and the lower edge of said bead is for a portion of its length coincident with the adjacent curved portion a^3 . In the unobstructed portion of the top a 50 circular depression or indentation a^7 is located, which provides a receptacle for the stopper of the inkstand.

The inkstand herein shown and described presents a symmetrical and highly-pleasing 55 effect as a whole. The curves are gradual and graceful, and the arrangement is such that an inkstand of attractive appearance is produced.

I claim as my invention—

60 The design for an inkstand, substantially as shown and described.

WILLIAM RODIGER.
